DESIGN FOR A CURTAIN OR SIMILAR ARTICLE

Gustave F. Erhard, Scranton, Pa.

Application January 22, 1936, Serial No. 60,732

Term of patent 3½ years

To all whom it may concern:

Be it known that I, Gustave F. Erhard, a citizen of the United States, residing at 2015 N. Washington Avenue, in the city of Scranton, county of Lackawanna, and State of Pennsylvania, whose post-office address is 2015 N. Washington Avenue, Scranton, Pennsylvania, have invented a new, original, and ornamental Design for a Curtain or Similar Article, of which the following is a specification, reference being had to the accompanying drawing, forming a part thereof.

Figure 1 is a plan view of a curtain embodying my new design. The portions between the broken lines is a continuation of the design illustrated in detail in the body of the curtain. The inter-

rupted lines in the body of the curtain illustrates mesh work.

Figure 2 is a detailed view of a portion of the curtain illustrating the mesh work illustrated in Figure 1.

The main characteristics of the design consists of a series of rows of perforations at the top of the curtain on a mesh background as illustrated in detail in Figure 2 and which extends over the entire curtain.

I claim:

The ornamental design for a curtain or similar article, as shown and described.

In testimony whereof I have signed this specification.

GUSTAVE F. ERHARD.
